UNITED STATES PATENT OFFICE.

WILLIAM R. JEAVONS, OF CLEVELAND, OHIO.

DESIGN FOR A HYDROCARBON-STOVE.

SPECIFICATION forming part of Design No. 34,251, dated March 19, 1901.

Application filed January 11, 1901. Serial No. 42,927. Term of patent 7 years.

To all whom it may concern:

Be it known that I, WILLIAM R. JEAVONS, a citizen of the United States, residing at Cleveland, in the county of Cuyahoga and State of Ohio, have invented and produced a new and original Design for Hydrocarbon-Stoves, of which the following is a specification, reference being had to the accompanying drawings, forming part thereof, and in which—

Figure 1 is a side elevation of the design, and Fig. 2 an end elevation looking in from the left of Fig. 1.

The stove as thus illustrated and embodied constitutes a complete and unitary design in which all the features shown are permanently associated and go together to the public; but the design thus shown still is dependent upon certain conspicuous and more essential features of its appearance, and which when displayed as in this design give an entirely new effect not hitherto seen in this class of stoves. Chief among these leading and material features and which are especially determining are the substantially drum-shaped burners B, standing out prominently in the midst of

a frame A, and which said frame has the appearance of a border inclosing said burners within the same, particularly as viewed in side elevation. Then as minor features there are displayed immediately in front of each burner an inclined stem 6, which rests at an upward and outward inclination to the burner and is surmounted by an ornamentation 7, directly in front of each burner, while at one end of the said frame A and outside said end there are displayed two circular figures 2 and 3 of different size, a stem 5 coming from within frame A, on which said circular figures are shown as mounted one above the other.

What I claim is—

The design for a hydrocarbon-stove, substantially as herein shown and described.

Witness my hand to the foregoing specification this 5th day of January, 1901.

WILLIAM R. JEAVONS.

Witnesses:

M. A. SHEEHAN,
R. B. MOSER.
